COMPANY, INC., OF NEW YORK, N. Y., A CORPORATION OF NEW YORK.

TELEPHONE-EXCHANGE SYSTEM.

Patented Oct. 8, 1918.

Application filed March 21, 1917. Serial No. 156,286.

ern:
LEWIS H. JOHNSON,
United States, residing at
100 Essex and State
Invented certain new
arts in Telephone-Ex-
change the following is a
exact description.
It is to telephone ex-
change being the provi-
ing means for such

object of this invention is to reduce the number of conductors required in the circuit of a ringing system, by using a four-party "selective code" ringing in which a button for each of the four parties is provided, the actuation of which will determine the character of ringing on the line, to simplify the circuits in which such a system is employed; and to so arrange such a ringing system that any additional station on a magnet may be manually connected to the system.

trated in the accom-
plich there is shown
phone exchange sys-
proper understand-

In the drawing, unit C connected with e A, and telephone meter of the common center of the magneto

ry line B there are E, F, G and H. At all bells are connected to the line and between the tip side of the call bell at the station of call bell is bridged through a back con-

ord circuit is a ring-
ising four buttons—
ession of any one of
wn contacts shown
sure. The contacts
l inclosure are only

operated when any one of the plungers of the ringing-key structure is in its way-down position, while the contacts associated with each plunger are actuated when the respective plungers are either in the way-down or an intermittent locking position. Associated with the ringing key structure are a plurality of relays which control the application of ringing current to the called line either over the ring or tip side thereof. Ringing current is supplied from generator 5 through interrupters 6 and 7. These two interrupters, as well as the third interrupter 8, are on the same shaft, which makes one revolution every six seconds. In this manner, when interrupter 6 is connected in circuit with generator 5 and the line, there is provided a ringing interval of two seconds, followed by a silent interval of four seconds, while if interrupter 7 be connected in circuit with generator 5 and the line, there is provided a ringing interval of one second, followed by a silent interval of one second, a ringing interval of one second, which is then followed by a silent interval of three seconds.

Assuming that the operator has been requested to make connection with station E on line B, the insertion of the plug into the jack of line B causes the operation of marginal relay 10 and cut-off relay 11. Since the call bell at station E is connected between the ring side of the line and ground, and is the first party on the line, plunger 1 of the ringing key structure will be depressed into its locking position, whereupon relay 12 is operated over a circuit from battery, through the winding of relay 12, contact of plunger 1, normal contact of relay 13, normal contact of tripping relay 14 and the contact of relay 10 to ground. The call bell at station E is therefore operated by ringing current from generator 5, over a circuit including the ringing segment of interrupter 6, normal contact of switching relay 15, winding of tripping relay 14, normal way-down contact of ringing key, right-hand normal contact of switching relay 16, lower alternate contact of relay 12, ring contacts of the plug and jack, ring side of the line and through the call bell at station E to ground. The subscriber at station E, responding, causes the operation of relay 14, whereupon relay 13 operates and

Bloomfield, in the count
5 of New Jersey, have in
and useful Improvemen
change Systems, of whi
full, clear, concise, and

This invention relates to change systems, its object being the provision of improved ring systems.

More specifically, the
tion is the reduction of
15 tacts in the ringing circuit commonly known as "selective" or "semi-selective" which there is a ringing circuit connecting the four stations on a line.
20 a button determining the ringing current sent over the wiring of the link circuit. Ringing systems are employed to organize the apparatus of
25 systems, that without the use of the apparatus a subscriber's net or local battery line is signaled.

This invention is illus-
30 panying drawing in wl
only so much of a tele-
tem as is necessary for a
ing of this invention.
there is shown a link circ
35 a calling telephone lin
lines B and D, the for
battery type and the la
or local battery type.

To the common batte
40 connected four stations
stations E and G the ca
ed between the ring si
ground, and at stations
bells are connected betw
45 the line and ground wh
the magneto line D the
across the line circuit t
tact of the switchhook.

Associated with the connecting-key structure comprising 1, 2, 3 and 4—the depression which controls way-down within the dotted inclosure shown within the dotted

locks up, thereby short-circuiting relay 12, which releases, removing the ringing current from the line, and completing the talking strands of the cord circuit.

5 Should station F have been desired, plunger 2, instead of 1, would have been depressed, causing the operation of relay 16 over a circuit from battery through the winding of relay 16, the alternate contact of plunger 2, normal contacts of relays 13 and 14 and the contact of relay 10 to ground. The operation of relay 16 closes a contact in circuit with relay 17. Relay 17 operates when interrupter 8 has rotated, so that the brush is in contact with the segment to which battery is connected, the operating circuit for pick-up relay 17 being from battery through the line segment and brush of interrupter 8, normal contact and winding of relay 17 and left-hand alternate contact of relay 16 to ground. Relay 17, in operating, completes a locking circuit for itself through its right-hand alternate contact, and causes the operation of relay 12 over a circuit from battery through the winding of relay 12, left-hand alternate contact of relay 17, normal contacts of relays 13 and 14 and the contact of relay 10 to ground. The call bell at station F is operated by current from generator 5 through interrupter 6 over the tip side of the line.

If station G had been desired, plunger 3 would have been depressed, causing the operation of relay 15 over a circuit from battery through the winding of relay 15, alternate contact of plunger 3, normal contact of plunger 2, normal contacts of relays 13 and 14, and the contact of relay 10 to ground. Relay 15, in operating, shifts the ringing circuit from interrupter 6 to interrupter 7, and following the operation of relay 15, when the brush of interrupter 8 has come in contact with the line segment to which battery is connected, pick-up relay 17 operates and locks up as hereinbefore described, the ground for this relay being supplied through the right-hand alternate contact of relay 15, instead of through the left-hand alternate contact of relay 16, as was the case when plunger 2 was depressed. Following the operation of relay 17, relay 12 operates. The call bell at station G is thereupon operated by current from generator 5 supplied through interrupter 7 over the ring side of the line.

Should station H have been desired, plunger 4 would have been depressed, whereupon relay 15 would operate over a circuit from battery through the winding of relay 15, left-hand alternate contact of plunger 4, normal contacts of plungers 3 and 2, normal contacts of relays 13 and 14 and the contact of relay 10 to ground. Relay 16 is also operated at this time, the circuit therefor being from battery through the winding of

relay 16, right-hand alternate contact of plunger 4, normal contacts of plungers 3 and 2, normal contacts of relays 13 and 14 and the contact of relay 10 to ground. The call bell at station H is thereupon operated 70 by current from generator 5, through interrupter 7 over the tip side of the line.

Should connection have been desired with the magneto line D, the insertion of the plug into the jack of that line would cause 75 the operation of cut-off relay 20 associated therewith. Relay 10 does not operate, however, for it is marginal and does not operate when connected in series with the cut-off relay of the magneto line which is of high 80 resistance. The resistance of the cut-off relays of common battery lines is low, so that when relay 10 is connected in circuit with a cut-off relay of a common battery line, it operates. To apply ringing current 85 to a magneto telephone line for the purpose of causing the operation of the call bell of the station on that line, the first plunger or button No. 1 of the ringing-key structure is depressed, thereby causing the operation of 90 relay 12 over a circuit from battery through the winding of relay 12, contact of plunger 1, normal contacts of plungers 2, 3 and 4, and the upper alternate way-down contact of the ringing key. The call bell at the station on the magneto line, which is connected across the line, is thereupon operated by current from grounded generator 5 through the lower alternate way-down contact of the ringing key, right-hand normal contact of 100 relay 16, lower alternate contact of relay 12, ring contacts of the plug and jack, over one side of line D, through the call bell at the station thereon, back over the other side of the line, tip contacts of the jack and plug, 105 upper alternate contact of relay 12 and left-hand normal contact of relay 16 to ground. The interrupter 6 and generator 5 may be considered as a source of ringing current of 110 one character, while interrupter 7 and generator 5 may be considered as a source of ringing current of another character. For all intents and purposes, so far as this invention is concerned, there may be separate generators producing currents of different 115 frequencies. It will be understood that the relay 15 determines which source of current shall be effective for signaling, while relay 16 determines the side of the line over which ringing current is to be projected. 120

What is claimed is:

1. A telephone exchange system comprising a telephone line, a link circuit connected with the line, sources of distinctive ringing current, an operator-controlled ringing key 125 in the link circuit, a relay controlled by the key for selecting the source of ringing current to be connected with the line, a relay controlled by the key for determining the side of the line over which current from the 130

selected source is to be projected, and a ringing relay controlled by the key for connecting the selected source to the line.

2. A telephone exchange system comprising a telephone line, a link circuit connected therewith, sources of distinctive ringing current, a ringing key in the link circuit, means controlled by the key for selecting the source of ringing current to be connected with the line, means controlled by the key for determining the side of the line over which current from the selected source is to be projected, and means controlled by the key for connecting the selected source to the line.

15 3. A telephone exchange system comprising a telephone line, a link circuit connected therewith, sources of distinctive ringing current, an operator-controlled ringing key in the link circuit, a relay controlled by the key for selecting the source of ringing current to be connected with the line, a relay controlled by the key for determining the side of the line over which current from the selected source is to be projected, and a ringing relay controlled by the key and coöperating with the selecting and determining relays for connecting the selected source to the line.

4. A telephone exchange system comprising a telephone line, a link circuit, a relay in the link circuit operating upon connection thereof with the line, an operator-controlled ringing key in the link circuit, sources of distinctive ringing current, a relay for selecting the source of ringing current to be connected with the line, a relay for determining the side of the line over which cur-

rent from the selected source is to be projected, both the selecting and determining relays being jointly controlled by the ringing key and by the first-mentioned relay, 40 and a ringing relay controlled by the determining relay and coöperating with the selecting and determining relays for connecting the selected source to the line.

5. A telephone exchange system comprising a common battery telephone line, a plurality of signal responsive devices connected therewith, a magneto telephone line having a signal responsive device connected thereto, a link circuit for connecting with either the 50 common battery or the magneto line, sources of distinctive ringing current, a ringing key equipped with a plurality of ringing buttons, one corresponding to each of the signaling devices connected with the common 55 battery line, means controlled by the ringing key for selecting the source of ringing current to be connected with the common battery line, a relay in the link circuit operating upon connection of the link circuit with the 60 common battery line to render the selecting means effective but not operating when the link circuit is connected with the magneto line whereby the selecting means is rendered 65 non-effective, and a relay controlled by one of the buttons of the ringing key to connect current from one of the sources to a magneto line.

In witness whereof, I hereunto subscribe my name this 20th day of March, A. D. 1917.

LEWIS H. JOHNSON.
